UNITED STATES PATENT OFFICE.

ISAAC LEWENTHAL, OF NEW YORK, N. Y., ASSIGNOR TO ROYAL METAL MANUFACTURING COMPANY, OF NEW YORK, N. Y., A CORPORATION OF NEW YORK.

DESIGN FOR A BELT.

SPECIFICATION forming part of Design No. 35,765, dated February 18, 1902.

Application filed December 21, 1901. Serial No. 86,861. Term of patent 7 years.

To all whom it may concern:

Be it known that I, ISAAC LEWENTHAL, a citizen of the United States, and a resident of the city and county of New York, borough of Manhattan, and State of New York, (whose post-office address is 120 Walker street, in said city,) have invented and produced a certain new and original Design for Belts, of which the following is a specification.

10 My invention relates to a design for a belt, and its essential features reside in the shape or configuration of the parts combined to produce a pleasant entirety.

Reference is had to the accompanying drawings, forming part of this specification, in which—

Figure 1 is a front elevation of the belt substantially as it appears in use. Fig. 2 is a rear elevation of the same, showing it at full length; and Fig. 3 is a front view of Fig. 2.

The belt-body comprises the intermediate short rectangular section 1 and the bands 2 3 extending therefrom, of greater vertical diameter intermediately than the intermediate section 1 and having longitudinal lines 4, formed by plaits or folds in the fabric, the

end triangular-like parts 5 6 having substantially vertical meeting edges 7 8, disposed when in use, as in Fig. 1, in line with the intermediate section 1 of the body, and downwardly and inwardly curving upper and lower edges 9 10, terminating on the points 11 12, the point 11 extending at an angle from the vertical meeting edges 7 8 of the two front pieces 5 6. At 13 is a rectangular ornament 35 extending over the intermediate section 1 of the body and portions of the bands 2 3.

The belt is so shaped or designed that when the parts 5 6 are placed together, as in Fig. 1, the central front portion will have a dip downward, the outer ends of the bands being secured to the clip 14 on the parts 5 6 at an angle to their vertical edges.

Having described my invention, I claim—

The design for a belt, substantially as herein shown and described.

Signed in the city, county, and State of New York this 19th day of December, 1901.

ISAAC LEWENTHAL.
